ANODE STRUCTURE FOR DOUBLE FILAMENT X-RAY TUBE

Zed J. Atlee, Chicago, Ill., assignor to Dunlee Corp., Chicago, Ill., a corporation of Illinois

Application August 12, 1952, Serial No. 303,945

7 Claims. (Cl. 313—56)

The present invention relates to X-ray generators and more particularly to an anode structure for an X-ray tube of the double filament type.

In my copending patent application, Serial No. 197,441, filed November 24, 1950, now United States Patent No. 2,671,867, issued March 9, 1954, entitled "Electrode Structure for X-Ray Tubes," I have described an electrode arrangement whereby the ratings of an X-ray tube may be greatly increased. For example, the ratings of a tube made in accordance with that patent, when operated self-rectified, are increased substantially to the full-wave rectified rating of the tube with a heretofore conventional electrode arrangement. This is accomplished, according to one modification, by the relatively simple expedient of tilting the anode face in the direction laterally of the longitudinal direction of the filament whereby the inverse electrons emitted from the anode face impinge harmlessly against the cathode head to one side of the filament and which is thereby safeguarded against destruction. Accordingly, the tube ratings may therefore be considerably increased as compared with those of conventional tubes.

The above mentioned prior application is concerned primarily with single filament X-ray tubes and it is a general object of the present invention to provide similar advantages in an X-ray tube of the double filament, or double focus type with an electrode arrangement whereby both of the filaments will be protected against the inverse electron flow.

As described in the above mentioned copending application, it has been my observation that the electrons emitted from the heated target of an X-ray generator, which electrons may for convenience be termed "inverse electrons," flow in a path perpendicular to the face of the target. In conventional tubes, in which the filaments are in line with the perpendicular of the corresponding anode spots, the inverse electrons will impinge upon the heated filament. Accordingly, when the tube is operated in a self-rectified manner, the electrons generated at the target impinge upon the filament during the inverse half cycle of the applied potential. These inverse electrons cause increased heating of the filament which in turn results in increased emission of electrons from the filament to result in still greater heating of the target. This, of course, further increases the inverse electron emission from the target creating a runaway condition of the tube that may result in destruction of the cathode filament.

It is an object of the present invention to provide a double filament type of X-ray generator in which the cathode and anode are so arranged that the cathode filaments are protected against destructive inverse electron emission from the anode.

A more specific object of the invention is to provide an X-ray generator of the double filament type in which the relative angular relation between the facing ends of the cathode and anode is such that the inverse electron emission from the anode focal spot of an energized

2

filament is directed in a laterally displaced relation with respect to the energized filament.

Other objects and advantages of the invention will become more apparent hereinafter.

- 5 The X-ray generator of the present invention includes a cathode unit having a pair of spaced-apart, longitudinally parallel cathode filaments focused to have their focal spots longitudinally parallel and relatively closely adjacent one another upon the anode target. A V-shaped target element mounted on the anode includes portions defining a separate planar target area for each of the electron beams generated by the cathode filaments, the face of each of the portions defining a plane inclined in a direction longitudinally of the corresponding cathode filament and, in addition, inclined at a second angle of inclination in a direction at right angles with respect to the first angle, the second angle of inclination being such that inverse electrons from the focal spot on the particular portion impinge harmlessly against the cathode structure in a laterally displaced relation with respect to the energized filament.

For a consideration of what is believed novel and inventive, attention is directed to the following description taken in connection with the accompanying drawings, while the features of novelty will be pointed out with greater particularity in the appended claims.

In the drawings,

Fig. 1 is a longitudinal elevation, partly in section, of a double filament X-ray generator embodying the present invention;

Fig. 2 is a fragmentary view of the anode and cathode parts taken along line 2—2 of Fig. 1;

Fig. 3 is a partial sectional view of the cathode and anode units taken along line 3—3 of Fig. 1;

Fig. 4 is a sectional view taken along the line 4—4 of Fig. 3;

Fig. 5 is a partial sectional view of the anode head taken along line 5—5 of Fig. 4;

Fig. 6 is an end view of the anode head taken along line 6—6 of Fig. 4; and

Fig. 7 is an end view of the cathode head taken along line 7—7 of Fig. 3.

The present invention is illustrated in connection with an X-ray generator or tube comprising coaxially mounted anode and cathode units 13 and 14 sealed within an envelope 17 preferably formed of glass.

The anode 13 is suitably mounted in the envelope 17 and sealed therein at one end of the envelope by a glass-to-metal seal 19 through which a portion 20 of the anode extends outwardly of the envelope to provide for cooling the anode.

The cathode unit 14 is likewise sealed in the envelope, preferably by a glass-to-metal seal 21 at the end of the envelope remote from the seal 19, the cathode being connected within the envelope to conductors 23 extending outwardly of the envelope through the seal 21 for the purpose of energizing the cathode from a suitable source of energizing current.

Referring particularly to Figs. 3 and 7, the cathode head facing the anode is provided with a pair of cathode means comprising a pair of elongated, longitudinally parallel electron focusing cup recesses 24 and 25 formed in the surface thereof facing the anode unit and in which are disposed the electron emitting filaments 26, 27 respectively which extend longitudinally of the cups. The filaments 26, 27 are suitably connected with the conductors 23 whereby they may be individually energized through any well known and suitable control circuit connected to supply current. The head end of the cathode 14 is formed with two plane faces 28, 29 disposed at a large obtuse angle in respect to one another and intersecting along a line perpendicular to the longitudinal axis of the

cathode head but offset slightly to one side thereof. The cathode faces 28 and 29 and the cups therein are arranged so that the electrons emitted by the cathode filaments are focused upon the anode target in elongated, longitudinally parallel focal spots 30, 31 (see Fig. 6) which are laterally spaced from each other but are relatively closely adjacent. As will be apparent, the angle between the cathode faces, the lateral distance between the filaments, and the distance between the filaments and the anode target must necessarily be correlated to obtain this end.

The anode unit 13 is preferably formed of a metal of relatively high heat conductivity such as copper. The face of the anode adjacent the cathode is recessed or indented and imbedded therein is a unitary reentrant or V-shaped target element 32, which element is preferably made of tungsten or other heavy metal not readily melted by the heat generated by the bombardment thereof by the electrons emitted from the cathode filaments. In accordance with the present invention, the target element 32 includes portions 34 and 35 defining a separate planar target area for each of the electron beams generated by the filaments 26, 27. The faces of portions 34 and 35 are inclined at an angle a toward each other relative to a plane perpendicular to the axis of the anode, which angle may be, for example, 20 degrees, but it is to be understood that this is by no means critical and may be varied considerably.

The faces 34 and 35 further intersect along a line 36 which extends in the same direction as the filaments but is inclined at an angle b with respect to a plane normal to the axis of the tube. The angle b may also be of the order of 20 degrees, but may be varied as desired so that X-rays generated by the impingement of the electrons upon the target will be directed outwardly of the envelope 17 as an X-ray beam 38 through a window portion of the side wall of the envelope.

While the angle of inclination a of the anode faces 34 and 35 may be varied, it is important that it be such that any perpendicular from the focal spot on the anode target should intersect the cathode unit at a point displaced laterally from the filament focused upon the particular target portion. For example, in Fig. 3 the cathode beam 40 from filament 27 is shown focused upon the target face portion 34 but all perpendiculars from the focal spot on the plane surface 34, representing the path of flow for the inverse electrons emitted from the focal spot and indicated by the dotted lines 41, strike the cathode head laterally displaced from the filament 27. It is of no consequence if the inverse electron beam impinges upon the cold inactive filament.

It has been found that the use of a unitary target element 32 defining both faces 34 and 35 is desirable in a double focused tube such as is illustrated. As mentioned above, the focal spots 30 and 31 are relatively closely adjacent, as is preferable in this type of tube for reasons which are well known and need not be explained in detail here. Should a separate target element be provided for each of the filaments, it will be apparent that the elements would be imbedded in the anode face, leaving a relatively narrow strip of copper therebetween. Since the focal spots are closely adjacent the line 36 between the two faces, the copper between the two separate faces might melt due to excessive heating, and which is avoided by using a unitary V-shaped target insert.

As in the case of the larger filament 27, the corresponding larger anode face portion 34 is offset in the direction toward the axis of the tube in order that the generated X-ray beam from this focal spot will be more nearly in line with the tube axis for facilitating greater accuracy in photographing or the like.

Having illustrated and described a preferred embodiment of the present invention, it should be apparent to those skilled in the art that the same permits of modification in arrangement and detail. I claim as my invention

all such modifications as come within the true spirit and scope of the appended claims.

I claim:

1. An X-ray generator comprising coaxially mounted 5 cooperating generally cylindrical anode and cathode units facing each other in a spaced relation, said cathode unit including a head having a pair of elongated, longitudinally parallel electron focusing cup recesses in the surface thereof facing said anode unit, an elongated, filamentary cathode element mounted longitudinally one in each of said cups, said cups focusing the electrons emitted by the respective cathode element upon longitudinally parallel and laterally spaced anode focal spots, said anode unit including a V-shaped unitary target element defining a separate 15 planar target portion for each of said focal spots, said portions being inclined toward each other at an angle of substantially 20° each relative to a plane perpendicular to the axis of said anode unit, the line of intersection of said planar portions being further inclined at an angle of substantially 20° relative to a plane perpendicular to the axis 20 of said units and extending in the same direction as said cathode elements, whereby all perpendiculars of the focal spot on the plane of either one of said portions will intersect said cathode head at a point laterally removed from the cathode element focused thereon.

2. An X-ray generator comprising coaxially mounted 25 cooperating cylindrical anode and cathode units facing each other in a spaced-apart relation, said cathode unit including a head having a pair of elongated, longitudinally parallel laterally spaced cathode elements positioned on opposite sides of the axis of said cathode unit and extending in the direction at right angles to said axis, said cathode elements being focused upon longitudinally parallel and laterally spaced anode focal spots, the longitudinal axis of each of said spots lying in a plane common with the axis of its corresponding cathode element, said anode including a unitary concave target element having two planar face portions defining separate target areas for each of said focal spots and inclined toward each other with an angle of substantially 140° 30 therebetween, the line of intersection of said planar face portions being inclined at an angle of substantially 20° relative to a plane at right angles to the axis of said cathode and anode units and extending in the same direction as said cathode elements.

3. An X-ray generator comprising cooperating coaxial anode and cathode units facing each other in spaced-apart relation, said cathode unit including a head having a pair of spaced-apart electron generating means each focused upon an anode spot closely adjacent to the anode focal spot of the other means, said anode unit having reentrant target means therein defining a separate planar target area for each of said focal spots, the face plane of each of said areas being inclined with respect to each other and each being inclined with respect to said cathode unit whereby the perpendicular projection from a target area intersects the cathode head to one side of the cathode means generating the electron beam focused thereon.

4. An X-ray generator comprising a cathode unit 55 having a pair of elongated, parallel, filamentary cathode elements and an anode unit facing said cathode unit, the face of said anode unit being recessed and including a pair of planar portions defining an obtuse angle therebetween, said planar portions intersecting along a line inclined at an acute angle with respect to the longitudinal axes of said cathode elements.

5. In a double focus X-ray tube, a cathode unit including a pair of substantially parallel, elongated filaments mounted in side-by-side, laterally spaced relation, an anode unit including a unitary, indented target element defining a pair of planar X-ray emitting surface defining portions angularly inclined toward each other at an included angle of less than 180 degrees, both of said

planar portions being angularly inclined with respect to the direction of said filaments.

6. In a double filament X-ray tube of the class described, an anode unit having a pair of reentering planar X-ray emitting surface defining portions, said planar portions being disposed at an angle of less than 180° with respect to each other.

7. A double focus X-ray generator comprising a cathode unit having a pair of substantially parallel, laterally spaced apart, elongate filaments, and an anode unit having an indented, unitary target element defining a pair of target areas angularly inclined toward each other.
